WEATHER STRIPPING

Joseph Sylvan, Detroit, Mich.

Application March 20, 1940, Serial No. 325,046

1 Claim. (Cl. 20—69)

This invention relates to improvements in weather strips of the type which fits in the recess or guide in the side jambs of a window frame in which the sash slides and one of the objects of the invention is to provide a self-adjusting weather strip of this character which will fit in the usual sash recess and which may move with the sash when the latter swells or shrinks, and is so constructed that at the same time it will continually bind against one face of the sash and will operate to hold the sash by friction, thereby rendering it possible to dispense with the usual counterweights or balances for small sashes.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention and in which

Figure 1 is a front elevation of a window sash having a weather strip in accordance with the principles of this invention applied thereto.

Figure 2 is a detail sectional view taken on line 2—2, Figure 1, on an enlarged scale.

Figure 3 is a detail perspective view of the weather strip.

The weather strip is preferably constructed of a single piece of sheet material bent into shape and consists of a body 10, portions of which are bent at right angles to each other, as at 11 and 12, to provide a weather strip of channel formation.

The end of the wall 11 is bent laterally and inwardly, as at 13, to form an overhanging flange spaced from the body 10 and the extremity of this flange 13 is preferably bent back upon itself, as at 14, to form a reinforcement.

Another portion of the body at the free edge of the wall 12 is bent back upon itself, as at 15, into the channel and against the wall 12. The extremity of the bent back portion 15 is deflected, as at 16, to form a laterally projecting and upwardly extending spring tongue portion 16 which is located within the channel. The portion of the tongue 16 adjacent the bent back portion 15 is preferably disposed in proximity to the base of the wall 12 and forms an angle 17.

The tongue 16 from the angle 17 extends upwardly and across the channel toward the opposite wall 11 beneath the flange 13, but terminates short of the wall 11 and the free edge of the tongue 16 is preferably bent back upon itself, 55

as at 19, to form a reinforcing portion for the edge.

The weather strip thus formed is adapted to be inserted into a groove or channel 21 in the window jamb 22 and substantially fills the groove. If desired, and in order to hold the weather strip against displacement, suitable fastening devices such as screws or nails 23, may be employed which pass through openings 24 in the body portion 10 adjacent the wall 12 and into a portion of the window frame.

In order to permit of the insertion of this fastening device, suitable apertures or openings 25 may be provided preferably in the angle 17 at the junction of the tongue 16 with the turned back portion 15 of the body of the weather strip. These openings 25 are in alinement with the openings 24 and when the fastening devices 23 are in position they will serve as an additional means for holding the tongue portion 16 of the weather strip in proper position.

The numeral 26 designates a window sash and is provided in one face thereof with a groove 27 running lengthwise of the sash and into this groove 27 the flange 13 and the turned back portion 14 on the wall 11 of the weather strip projects and moves.

This groove 27 is so located with respect to the edge 28 of the window sash that when the sash is in position the edge thereof will project into the channel and will place the tongue 16 under tension. This will cause the free edge of the tongue 16 to press against the sash 26 and co-operating with the groove 27 and the flange 13 serves not only as a friction means for holding the sash 26 in position but the tongue will yield under expansion of the window sash and will remain in contact with the edge of the sash during contraction and expansion of the sash.

In addition to the spring tongue 16 the walls 11 and 12 of the channel are also resilient, and by reason thereof they will be held in contact with the side walls of the groove in which the weather strip is located.

While the preferred form of the invention is herein shown and described, it is to be understood that various changes may be made in the details of construction and in the combination and arrangement of the several parts within the scope of the claim without departing from the spirit of this invention.

What is claimed as new is:

As an article of manufacture, a weather strip of integral construction formed of sheet metal and comprising a body, a portion of which is

shaped to form a wall extending along one of the lateral edges thereof, the free edge of said wall being bent inwardly to form a flange extending along said wall, overhanging and spaced from said body for a considerable distance, said flange being substantially parallel with the body, the opposite edge of said body being bent to form a wall substantially parallel with the first said wall at a substantial distance from the free edge of the said flange, a portion of the second said wall being bent back upon itself and against the

inner face thereof, the said bent back portion itself being deflected on a line adjacent the junction of the second said wall and the said body to form a spring tongue extending in an inclined direction from the said line, away from the said body toward the flange on the first said wall and projecting under said flange, said tongue terminating short of and spaced from the first said wall, the free edge of the tongue being normally spaced from the said flange.

JOSEPH SYLVAN.
